Inventor.

UNITED STATES PATENT OFFICE.

WILLIAM A. SPICER, OF PROVIDENCE, RHODE ISLAND.

DESIGN FOR A PORTABLE COOKING-RANGE.

Specification forming part of Design No. 6,155, dated September 24, 1872.

To all whom it may concern:

Be it known that I, WILLIAM A. SPICER, of the city and county of Providence and State of Rhode Island, have invented and produced a new and original Design for a Portable Cooking-Range, of which the following is a specification:

The nature of my design is fully represented in the accompanying photographic illustration, to which reference is made.

J represents a front elevation of a portable cooking-range. A B represent a molding round the body of the range, at the top and bottom of the same. C and D represent a molding running round the top and base of the range. E E E and F F F represent an ogee and flat raised molding round the pan-

els of doors and panels on doors. G and H represent panel and rosette finish on doors of range, and the word "Medallion" in raised letters on the doors of the same.

What I claim as my invention is—

Design for a portable cooking-range, ornamented with the moldings, panels, and rosette finish, of the style and combined as shown in accompanying photographic illustration; also, the word "Medallion" in raised letters, arranged, used, and combined with the stove-doors for ornamentation, substantially in the manner as above described and set forth.

WILLIAM A. SPICER.

Signed in presence of—

HENRY W. ALLEN,
FRANCIS V. KELLY.
